United States Patent Office

Des. 205,577

Patented August 16, 1966

205,577

SAFETY PIN

Ralph F. Van Dean, Morristown, N.J., assignor to R. N. Miksel Corporation, Orange, N.J., a corporation of New Jersey

Filed Dec. 2, 1964, Ser. No. 82,871

Term of patent 14 years

(Cl. D86—10)

FIG. 2

FIG. 1 is a perspective view of a safety pin showing my new design, both faces being identical; and

FIG. 2 is an edge view showing the cover member.

I claim:

The ornamental design for a safety pin, as shown and described.
